Clarendon Chamberlain, Attn:

By

UNITED STATES PATENT OFFICE

EDWIN H. MILLER, OF CHICAGO, ILLINOIS, ASSIGNOR TO NORRIS ALISTER-BALL COMPANY, A CORPORATION OF OHIO.

ALARM CLOCK.

1,402,524.

Specification of Letters Patent.

Patented Jan. 3, 1922.

Application filed August 11, 1921. Serial No. 491,340.

To all whom it may concern:

Be it known that I, EDWIN H. MILLER, a citizen of the United States, residing at the city of Chicago, in the county of Cook and State of Illinois, have invented certain new and useful Improvements in Alarm Clocks, of which the following is a specification.

My invention relates to alarm clocks which provide visual means by which it can be known under all conditions, whether the mechanism is properly set to give the alarm. In addition to the time-keeping mechanism and the alarm mechanism associated therewith, standard alarm clocks are usually provided with a control device by which the alarm when wound and set for the desired time, by a movement of the shut-off lever external to the casing, may be locked at the "silent" or unlocked by moving it to the "alarm" point.

But it may happen that through inadvertence the control device is not moved to unlock the striking mechanism in the "alarm" position; and that the user cannot recall after the light is extinguished, whether he has properly moved the shut-off lever to the "alarm" point.

It is the object of my invention to provide a luminous signal which always will be visible in the dark when the alarm mechanism is in striking position, but which will be invisible when the alarm mechanism is not in proper position to give an alarm.

The principles of my invention are illustrated in the drawings in which Fig. 1 shows a front elevation of an alarm clock embodying my improvement. Fig. 2 is a perspective view of the same looked at from the left and from above. Fig. 3 is a similar view with the front portion of the casing removed. Fig. 4 is a similar view showing an alternative construction. Fig. 5 is a section on the line 5—5 of Fig. 3.

Further describing my invention with reference to the drawings in which like characters of reference denote like parts throughout, 1 is the usual drawn metal cup or foundation piece within which the mechanism of an ordinary alarm clock is mounted. 2 is the rear section of the outer casing which is secured to the foundation cup and which acts as a bell when struck by the hammer 3 which passes through the opening 4 to

contact with said bell. The dial plate 5 is supported by the flange 6 of the framework and is normally secured in place by the front section 8 of the outer casing which also has a flange 9 to engage the edge of the protecting glass 10. A shut-off or locking slide 12 is placed inside the foundation cup in which it is secured by means of a lug having a head 14 and the body piece 15 which passes through the keyhole slot 16 and is upset to attach it to the slide. In order that the slide may further be guided a second slot 16' is formed in the foundation cup 1, and a lever 17 is attached to the said slide by means similar to that last described. Said lever is extended upwardly, however, and includes a screw 18 which passes through the slot 19 in the outer casing. Said slide is adapted to engage the hammer 3 and prevent it from sounding when the lever 18 is moved to the right, and to free it when moved to the left, as indicated in Fig. 2.

The outer casing 8 of the clock has an annular flange 20 in which is placed a sight opening 21, and back of said opening on the dial 80 is provided a luminous spot or glower 22. Said spot is formed by the application, at the proper position with reference to said sight opening, of any self-luminous material such as zinc sulfide combined with suitable salts of radium, thus forming a glow spot or glower which, unobstructed, will show in the dark through the said window or opening.

Referring to Fig. 3; the shield piece 23 is mounted upon the shut-off lever 17 and held in place by the screw head 18 or by any suitable means. The shield piece has an overhung portion 24 in such position with reference to the alarm lever and the glow spot that when the alarm is locked by the slide 12 in the "silent" position, the overhung portion 24 will close the sight opening 21 and conceal the glower, but when the shut-off lever is moved to the "alarm" position the said overhung portion will be moved with it so that the sight opening will be unobstructed and the glower 22 disclosed.

A slight modification of my device is shown in Fig. 4 in which the movable shield piece 23' attached to the shut-off lever 17 is provided with an overhung por-

tion 28 upon which the self-luminous compound 28' is placed. This overhung portion is in such position with reference to the shut-off lever and the sight opening that, when the alarm is locked in the "silent" position, the glow spot will be within the casing and invisible; but when the shut-off lever is moved to the "alarm" position the glow spot will register with the sight opening and be visible therethrough.

In either case, however, the result is the same, that a complete illuminated visual indication is given whenever the alarm striker is adapted for operation; but that, when no positive signal is given, the same is in inoperative position.

I have illustrated my invention by reference to a practical and operative application thereof in connection with an alarm clock of standard construction. But I am not limited to any particular form of alarm clock construction as my invention may be used whenever means is provided for locking or freeing the alarm mechanism by a correspondingly alternatively movable device, to indicate a predetermined position thereof.

I claim:—

1. In an alarm clock; a casing having a sight opening, a glower operatively disposed relatively to said opening, a movable device for controlling the alarm striking mechanism, and means associated with said movable device for causing said glower to be exhibited at said sight opening to indi-

cate a predetermined condition of the said striking mechanism.

2. In an alarm clock; a casing having a sight opening, a glower adapted to be exhibited at said opening, a movable device including a shut-off lever for controlling the alarm striking mechanism, and a shield piece having a depending member and movable by said shut-off lever relatively to said opening, whereby said glower may be exhibited therethrough, to indicate a predetermined condition of the said striking mechanism.

3. In an alarm clock; a casing having a sight opening, a glower fixed in the rear of said opening, a movable device including a shut-off lever for controlling the alarm striking mechanism, and means associated with said movable device for closing said sight opening when the alarm striking mechanism is in inoperative position.

4. In an alarm clock; a casing having a sight opening, a glower fixed in the rear of and adapted to be exhibited at said opening, a shut-off lever for controlling the alarm striking mechanism, a shield piece on the shut-off lever, and a depending member on said shield piece movable relatively to said opening whereby said opening may alternatively be opened or closed by corresponding movements of the shut-off lever.

In witness whereof I have hereunto set my hand at Chicago, Illinois, this 9th day of August, 1921.

EDWIN H. MILLER.
